ATTORNEYS

UNITED STATES PATENT OFFICE.

HOWARD COCHRAN EVANS, OF LYNCHBURG, VIRGINIA.

POULTRY DEVICE.

1,384,054.

Specification of Letters Patent.

Patented July 12, 1921.

Application filed July 28, 1920. Serial No. 399,513.

To all whom it may concern:

Be it known that I, HOWARD COCHRAN EVANS, a citizen of the United States, and a resident of Lynchburg, in the county of Campbell and State of Virginia, have invented certain new and useful Improvements in Poultry Devices, of which the following is a specification.

My invention relates to and has for its object the provision of a poultry device adapted for use within a brooding room for preventing young chickens from crowding in the corners or at the sides of the room and thus becoming smothered or unduly heated with the obvious disastrous results.

I will describe one form of device embodying my invention and will then point out the novel features thereof in claims.

In the accompanying drawings:

20 Figure 1 is a view showing a brooding room having applied thereto a plurality of devices embodying my invention.

Fig. 2 is an enlarged detail perspective view of one of the devices shown in Fig. 1.

25 Fig. 3 is a vertical sectional view taken of Fig. 2.

Referring specifically to the drawings in which similar reference characters refer to similar parts, B designates generally a pair 30 of brackets, each of which is preferably formed of metal and includes a vertical portion 15 connected at its upper end to an inclined portion 16, a relatively short vertical portion 17 connected to the lower end of 35 the inclined portion, and feet 15^a and 17^a formed on and disposed at the lower ends of the vertical portions 15 and 17, respectively. The inclined portions 16 are rigidly connected to each other by means of a board 40 D which is secured thereto by means of rivets 18. The board D constitutes an inclined platform which terminates at its lower end at a point flush with the upper ends of the short vertical portions 17.

45 The portions 17 are connected by a strip S which is of a width to provide a suitable space between its upper edge and the lower edge of the board D. Within this space is arranged a plurality of rollers R supported 50 for rotary movement upon a common shaft T journaled in bearings 19 secured to the vertical portion 17.

In the applied position of the device within a brooding room as shown in Fig. 1, it is 55 secured to the floor by means of the feet 15^a

and 17^a, the device being arranged along the sides of the room or in spanning relation to the corners of the room. I preferably provide a plurality of these devices for each room and arrange such devices in the manner shown in Fig. 1, although it is to be understood that they may be arranged in any manner so long as the points along the sides and corners of the room are protected.

In operation, the young chickens being 65 prevented from gaining access to the walls and corners of the room, tend to roost in front of the strip S. Those chickens attempting to climb over the ones roosting in front of the strip S light onto the board D 70 and because of the inclination of the latter slide down onto the rollers R where they are precipitated onto the floor of the brooding room. Other chicks, in climbing over the roosting chickens, will light 75 directly on the rollers R so that they too are precipitated onto the floor. In either instance, the chickens are distributed uniformly in front of each device so that they are prevented from congregating at any 80 one point along any one device. This obviously prevents crowding of the chickens and eliminates any possibility of the chickens smothering each other and becoming unduly heated. The space at the opposite sides 85 of the rollers R allows of the free circulation of air to the chickens roosting in front of the strip S.

It is to be particularly noted that the distance from the lower edge of the strip S to 90 the lower edge of the board D is such that with the chickens roosting directly in front of the strip S their heads are kept raised from the floor of the brooding room because of the inclination of the board, thus preventing 95 them from crowding with their heads on the floor.

Although I have herein shown and described only one form of device embodying my invention, it is to be understood that 100 various changes and modifications may be made herein without departing from the spirit of the invention and the spirit and scope of the appended claims.

What I claim is:

1. A poultry device of the character described comprising, an inclined floor, and a plurality of rollers mounted for rotary movement beneath the lower edge of the floor.

105

110

2. A poultry device of the character described comprising, a floor supported in inclined position with respect to the vertical, and a roller supported for rotary movement and disposed beneath and in spaced parallel relation to the lower edge of the floor. 20
3. A poultry device of the character described comprising, a pair of brackets, each of the brackets comprising a vertical portion, a second vertical portion relatively longer than the first vertical portion, an inclined portion connecting the two at their upper edge, a floor connecting the inclined portions of said brackets, a strip connecting the first vertical portion to said brackets and spaced from the adjacent edge of said floor, a shaft journaled on the first vertical portion and disposed between said strip and
4. In combination, a brooder, and an inclined floor arranged in spanning relation to the floor and a side wall of the brooder, with the lower edge of the floor spaced from the brooder floor. 25
5. In combination, a brooder, an inclined floor arranged in spanning relation to the floor and a side wall of the brooder, with the lower edge of the floor spaced from the brooder floor, and a plurality of rollers supported for independent rotary movement and disposed beneath and in substantially spaced parallel relation to the lower edge of the floor. 30

HOWARD COCHRAN EVANS.
